HARRY BLAND STRANGE, OF BLACKHEATH, ENGLAND, ASSIGNOR TO THOS. FIRTH AND SONS, LIMITED, OF SHEFFIELD, ENGLAND.

ARMOR-PIERCING PROJECTILE.

1,149,602.

Specification of Letters Patent. Patented Aug. 10, 1915.

Application filed April 25, 1914. Serial No. 834,505.

To all whom it may concern:

Be it known that I, HARRY BLAND STRANGE, subject of the King of England, residing at Blackheath, Kent, in England, 5 have invented certain new and useful Improvements in Armor-Piercing Projectiles, of which the following is a specification.

This invention relates to armor-piercing projectiles and has for its object to improve 10 the penetrating qualities of pointed nosed projectiles of the type in which the point is covered by a cap which in turn is generally inclosed in or has mounted on its face a hollow casing.

15 According to this invention a projectile is provided with a built-up cap which comprises concentric inner and outer portions the inner portion having a nose which forms a central protrusion. The nose of the inner 20 cap member or the whole of that member may be hardened and tempered.

In a cap thus made advantage is taken of the fact that the caps of modern armor-piercing projectiles are considerably heavier 25 relatively to the projectile proper than was formerly the case. Hence, the energy stored in the cap itself is an appreciable factor and this energy is utilized to cause the nose of the cap to have some destructive effect on 30 the armor plate attacked. It may be said that the whole cap acts as if it was a small projectile fired at the face of the plate, the projectile itself, striking in the spot which has already been damaged by the heavy cap, 35 effects perforation of the plate with a minimum of damage to its point. The nose of the inner cap may be broken up on or immediately after impact or in some cases it may be displaced or deformed, but in any 40 case its action is intended to be preparatory to that of the point of the projectile proper.

The outer cap member may in some cases be built up of two or more concentric members and while its forward portion constitutes mainly what may be termed and in some instances may be regarded as the true face of the cap the remainder provides support for the inner cap and for that part of the head of the projectile which lies to 50 the rearward of the part which is inclosed in the inner cap.

The nose of the inner cap may be of any suitable shape but when, as is sometimes desirable, it has a pointed ogival form, a suitably thick layer of relatively soft and due-

tile material such for instance as that of which the outer cap member is formed is disposed over or in front of the pointed nose of the inner cap member so as to form a supplementary cap. Such a supplementary cap may be used whatever the shape of the protruding nose of the inner cap, but it is primarily intended for use when that nose is pointed to give the point additional support on impact in a manner similar to 65 that in which the metal forming the mass of the main cap supports the pointed end of the projectile proper.

When a supplementary cap is employed it may be disposed or formed in various ways. Thus for example, it may be actually mounted on the nose of the inner cap member so as to cover over and incase it and either be formed integral with the outer cap member or be applied and attached to the 70 face of this outer cap member through which face the nose of the inner cap protrudes. Alternatively where, as is desirable, a hollow nose or casing covers over the hollow face of the cap the supplementary cap may form an integral part of this 75 hollow casing or be mounted therein or attached thereto in some convenient manner. In this case the supplementary cap is not directly in contact with the nose of the inner cap member which protrudes from the surrounding true face of the outer cap member but is positioned somewhat in advance of the nose of the inner cap member. Thus for example, the forward end of the 80 hollow casing may be substantially thickened to form the supplementary cap which thus is integral with and formed of metal having the same qualities as that employed in the construction of the hollow casing, the 85 latter being attached to and mounted on the outer cap member in some convenient manner.

The accompanying drawings are longitudinal central sections through the front portions of various constructions of projectiles all according to this invention.

In Figure 1 the pointed ogival nose A of the projectile is furnished with an inner cap member B surrounded by an annular concentric outer cap member C. The nose of the inner member B protrudes beyond the face of the built-up cap *i. e.* the face C' of the outer cap member C. In this form the hollow nose or casing D is screwed on to the 105 110

outer cap member C. In this figure, as in all the other figures, cross-hatching on a part or the whole of the inner cap indicates by way of example, that the part so marked is hardened and tempered.

5 The cap illustrated in Fig. 2 is generally similar to that described with reference to Fig. 1 except that the nose of the inner cap B is extended through the space inclosed by the casing D and fills a central hole left in the end of that member.

10 In Fig. 3 a projectile is shown in which the inner cap member B provides the greater part of the whole weight of the cap. In this form the outer cap member C is attached to the inner cap and does not itself extend back into contact with the shoulders of the projectile proper. As in Figs. 1 and 15 2 the hollow nose D is secured to the outer cap member.

20 The projectile illustrated in Fig. 4 differs from those already described by having the hardened protruding nose B² of the inner cap B pointed and in order that this point shall, after impact, have some support, the nose of the hollow casing is thickened up as at C² to form a supplementary cap. In this construction the hollow nose or casing of the projectile is integral with the outer cap member C.

25 Fig. 5 shows a projectile similar to that illustrated in Fig. 1 but having an outer cap member built up of two concentric annular portions C⁴ and C⁵.

30 In the projectile illustrated in Fig. 6 the inner cap member B is hardened and tempered all over as shown by the cross-hatching. It has a pointed nose protruding beyond the plane of the true face of the cap. 35 This pointed extremity is covered by a supplementary cap C⁶ which, in this example, is integral with the outer cap member C and in contact with the point of the inner cap. As in the construction illustrated in Fig. 3, the outer cap member is attached to the inner cap member and the hollow nose or casing D is formed separately from the outer cap member to which it is attached by a screw joint.

40 The projectile shown in Fig. 7 has a pointed inner cap hardened all over as in Fig. 6, but the weight of the inner cap relatively to that of the outer cap is smaller in Fig. 7 than in Fig. 6 and the outer cap metal in Fig. 7 extends down on to the shoulders of the projectile proper. A further feature of the projectile illustrated in Fig. 7 is that the supplementary cap C⁷ is formed separately from the outer cap member C instead of being made integral with it.

45 It will be noticed that in all the constructions where the inner cap member B has a hardened pointed nose a supplementary cap is provided in some form or another. The object of this is to give some amount of sup-

port to the point of the inner cap while it is doing its preparatory work on the armor plate.

50 When the whole of the inner cap member is hardened, as for example in the constructions shown in Figs. 6 and 7, its internal surface may be separated from the hard pointed nose of the projectile proper by a thin layer of soft steel or other suitable material. This facilitates the fitting of the two parts and tends to distribute the stress between the two hardened members.

55 Although certain of the figures show the inner cap having its nose hardened, it is to be understood that the hardened nose or point may, if desired, be formed separately from the other part of the inner cap to which it may be fastened by any suitable mechanical means.

60 The detail form of the members of which the complete cap is built up may vary to suit requirements but it will be appreciated that the improved construction enables the inner cap to be made of any metal most suited to fulfil the object to be attained by the protruding nose whether this nose is hardened or not, while the outer member can be formed of metal having other physical properties which will make it best suited to do the work which it is to be called upon to perform. Thus, for example, the inner cap may be made of nickel-chrome steel while the outer member can be formed of mild steel, but it is to be understood that if desired, both cap members may be constructed of mild steel or both of nickel-chrome steel.

65 The relative dimensions of the parts constituting the built-up cap and more particularly the amount of hardened and relatively soft metal covering the point of the projectile may vary in accordance with requirements and the nature of the objective plate attacked.

70 What I claim as my invention and desire to secure by Letters Patent is:—

75 1. In combination with an armor-piercing projectile having an ogival point to the projectile proper, a cap built up over said ogival point and comprising an inner member and an outer member, both members formed of steel or an alloy thereof, the inner member having a nose which protrudes centrally beyond the main face of the cap, and a hollow casing disposed over the cap.

80 2. In combination with an armor-piercing projectile having an ogival point to the projectile proper, a cap built up over said ogival point and comprising an inner member and an outer member concentric to the inner member, both members formed of steel or an alloy thereof, the inner member having a nose which protrudes centrally beyond the outer concentric member, and a hollow casing disposed over the cap.

3. In combination with an armor-piercing projectile having an ogival point to the projectile proper, a cap built up over said ogival point and comprising an inner member and an outer member, both members formed of steel or an alloy thereof, the inner member having a nose which is hardened and tempered and which protrudes centrally beyond the main face of the cap, and a hollow casing disposed over the cap. 50
4. In combination with an armor-piercing projectile having an ogival point to the projectile proper, a cap for said projectile, comprising an inner part which covers the ogival point and has a projection which protrudes centrally beyond the main face of the cap, said projection arranged for deformation on impact before the cap metal lying around and to the rear of the point is displaced, and an outer part providing a support for the inner part of the cap and also for that part of the head of the projectile which lies to the rearward of the point inclosed in said inner part, and a hollow casing disposed over the cap. 65
5. In an armor-piercing projectile a built-up cap comprising an inner portion of steel or an alloy thereof hardened and tempered at the nose and an outer concentric portion also of steel or an alloy thereof but soft relatively to the inner portion, the nose of the inner portion protruding beyond the true face of the cap which is formed mainly by the annular outer portion. 70
6. In an armor-piercing projectile a built-up cap comprising an inner portion and an outer annular portion composed of a plurality of concentric parts the nose of the inner portion protruding beyond the true face of the cap which is formed mainly by the annular outer portion. 75
7. In an armor-piercing projectile the combination with a built-up cap comprising concentric inner and outer portions the inner portion being wholly hardened and tempered and having its nose shaped so as to protrude centrally beyond the main face of the cap, said main face being formed by the outer concentric portion of the cap, of a supplementary cap of relatively soft material disposed over the protruding nose of the inner cap member. 80
8. In an armor-piercing projectile the combination with a built-up cap comprising concentric inner and outer portions the inner portion being wholly hardened and tempered and having its nose shaped so as to protrude centrally beyond the main face of the cap, said main face being formed by the outer concentric portion of the cap, of a supplementary cap of relatively soft material disposed over the protruding nose of the inner cap member such supplementary cap being integral with the outer cap member. 85
9. In an armor-piercing projectile the combination with a built-up cap comprising concentric inner and outer portions the nose of the inner portion forming a central protrusion, of a hollow nose or casing and a supplementary cap in front of the point of the inner cap such supplementary cap being carried by the hollow nose or casing. 90
10. In an armor-piercing projectile the combination with a built-up cap comprising concentric inner and outer portions the nose of the inner portion forming a central protrusion, of a hollow nose or casing and a supplementary cap in front of the point of the inner cap such supplementary cap being integral with the hollow nose or casing. 95

In testimony whereof I have signed my name to this specification in the presence of two subscribing witnesses.
